ATTORNEY

UNITED STATES PATENT OFFICE

ION VON KERT HOTT, OF DAYTON, OHIO, ASSIGNOR TO THE JOYCE-CRIDLAND COMPANY, OF DAYTON, OHIO, A CORPORATION OF OHIO

MULTIPLE-LIFT SCREW JACK

Application filed March 13, 1926. Serial No. 94,396.

The invention relates to multiple lift screw jacks and one object of the invention is to provide such a jack in which all threaded parts will be protected.

5 A further object of the invention is to provide such a jack having a plurality of chambers to contain lubricant.

10 A further object of the invention is to provide such a jack with means whereby the operating crank may be applied to one part thereof to actuate the jack and to another part thereof to lift the jack as a whole, to place the same under the part to be lifted.

15 Other objects of the invention will appear as the jack is described in detail.

In the accompanying drawings Fig. 1 is a side elevation of a jack embodying my invention; and Fig. 2 is a vertical sectional view taken centrally through such a jack.

20 In these drawings I have illustrated one embodiment of my invention but it will be understood that this particular embodiment has been chosen for the purpose of illustration only and that the parts may take various forms and may be arranged in various ways without departing from the spirit of the invention.

25 As here shown, the jack comprises a hollow standard 1 having an enlarged lower portion 2 constituting a base. The upper portion of the standard is cylindrical and is provided with internal screw threads 3. Mounted within the threaded portion of the standard and engaging the threads thereof is an axially movable member, which is preferably in the form of a nut 4, adapted to travel lengthwise of the standard. Rigidly secured to the nut 4 is a screw 5, which, in the present instance, is hollow and has an unthreaded lower portion 6 extending through the nut 4 and rigidly secured thereto, as by means of a pin 7, thus causing the nut and the screw to rotate in unison. Mounted for axial movement to the standard is a hollow lifting element 8 the lower portion of which is provided with internal screw threads, as shown at 9, and thus constitutes a nut which is rigid with the lifting element. The screw 5 extends through this nut. Consequently 50 when the nut and screw are rotated the screw

will move axially of the standard with the nut and the rotation of the screw will cause the lifting element to move axially with relation to the nut, thus providing a multiple lift for the lifting element. Interposed between the standard and the lifting element is a sleeve 10 which has axial movement with the nut and which is so connected with the standard as to be held against rotation therewith and is so connected with the lifting element as to hold the latter against rotation with relation to the sleeve. Further, this sleeve cooperates with parts carried by the standard and the lifting element to limit the outward movement of the sleeve and nut 65 with relation to the standard and to limit the outward movement of the lifting element with relation to the sleeve, thus preventing the nut 4 from being moved out of engagement with the threads of the standard and preventing the lifting element from being lifted out of engagement with the screw. As here shown, this sleeve rests loosely upon the nut 4 so that it will have axial movement therewith but will not rotate therewith, and is provided in one side with a longitudinal slot 11 into which extends a stud 12 mounted in the standard 1 near the top thereof. The sleeve has a second slot 13 which, in the present instance, is arranged opposite the slot 11 70 and into which extends a stud, such as a screw 14, carried by the lower portion of the lifting element. The nut 4 and screw 5 may be rotated in any suitable manner but preferably the screw is hollow and an actuating bar 15 is rotatably mounted in the base 2 of the standard and extends into the hollow screw, the opening in the screw and the actuating bar being non-circular in cross section so that the screw, 85 and the nut which is rigidly secured thereto, will be caused to rotate with the actuating bar and will have free sliding movement with relation thereto. Rigidly secured to the actuating bar 15 and arranged within the base 2 is a beveled gear 16 with which meshes a beveled pinion 17 journaled in a bearing 18 in the side wall of the base and having at its outer end a squared stud 19 adapted to receive a socket 20 carried by an operating 90 95 100

member or crank 21. Obviously the rotation of this crank when applied to the stud 19 will actuate the gear 16, screw 5 and nut 4, thus imparting axial movement to the lifting element.

5 It is often necessary to place a jack of this kind under a part to be lifted which is more or less difficult of access, such, for example, as the axle of an automobile. In order that 10 the jack may be conveniently lifted as a whole and moved into its proper position with relation to the part to be lifted I have secured to the standard 1 a stud 22, which, in the present instance, comprises the enlarged head of 15 the stud 12. This stud is adapted to receive the socket 20 of the operating crank 21 and is so arranged that the jack may be conveniently lifted by the crank.

It will be noted that the arrangement of 20 the mechanism is such as to provide a series of chambers adapted to receive lubricant. For example, the base and the hollow lifting element may both contain lubricant and lubricant may also be placed in the standard between the lifting element and the nut. In 25 this manner the several operating parts are thoroughly lubricated at all times and there is little, if any, tendency for the grease to work out to the exterior of the jack.

30 While I have shown and described one embodiment of my invention I wish it to be understood that I do not desire to be limited to the details thereof as various modifications may occur to a person skilled in the art.

35 Having now fully described my invention, what I claim as new and desire to secure by Letters Patent, is:

1. In a lifting jack, a hollow standard having internal screw threads, a member rotatably mounted in said standard and having threads engaging the threads of said standard, a screw mounted in said standard, connected with said member for axial movement therewith and having external screw threads, 45 a lifting element having threaded engagement with said screw, and means for rotating said threaded member and said screw.

2. In a lifting jack, a hollow standard having internal screw threads, a member rotatably mounted in said standard and having threads engaging the threads of said standard, a screw mounted in said standard, connected with said member for axial movement therewith and having external screw threads, 55 a lifting element having threaded engagement with said screw, means for rotating said threaded member and said screw, and means for holding said lifting element against rotation with said screw.

65 3. In a lifting jack, a hollow standard having internal screw threads, a member rotatably mounted in said standard and having threads engaging the threads of said standard, a screw rigidly secured to said member, 70 a hollow lifting element having internal

screw threads to receive said screw, and means for rotating said threaded member and said screw.

4. In a lifting jack, a hollow standard having internal screw threads, a member rotatably mounted in said standard, and having threads engaging the threads of said standard, a screw rigidly secured to said member, a hollow lifting element having internal screw threads to receive said screw, 75 means for rotating said threaded member and said screw, and means for holding said lifting element against rotation with relation to said standard.

5. In a lifting jack, a hollow standard having internal screw threads, a member rotatably mounted in said standard and having threads engaging the threads of said standard, an externally threaded screw mounted in said standard and connected with 85 said member for axial movement therewith, a lifting element having threaded engagement with said screw, a sleeve mounted about said lifting element between the same and said standard, said sleeve being held against 90 rotation with relation to said standard and having means for holding said lifting element against rotation with relation thereto, and means for rotating said threaded member and said screw. 95

6. In a lifting jack, a hollow standard having internal screw threads, a member rotatably mounted in said standard and having threads engaging the threads of said standard, an externally threaded screw mounted in said standard and connected with 100 said member for axial movement therewith, a lifting element having threaded engagement with said screw, a sleeve mounted about said lifting element between the same and said standard and having axial movement with said threaded member, means to limit the axial movement of said sleeve and to hold same against rotation, means to limit the axial movement of said lifting element with 105 relation to said sleeve and to hold the same against rotation with relation thereto, and means for rotating said threaded member and said screw. 110

7. In a lifting jack, a hollow standard having internal screw threads, a member rotatably mounted in said standard and having threads engaging the threads of said standard, an externally threaded screw mounted in said standard and connected with 115 said member for axial movement therewith, a lifting element having threaded engagement with said screw, a sleeve mounted about said lifting element between the same and said standard and having longitudinal slots, a stud carried by said standard and extending into one of said slots, a stud carried by said lifting element and extending into the other of said slots, and means for rotating said threaded member and said screw. 120 125 130

8. In a lifting jack, a hollow standard having internal screw threads, a nut rotatably mounted in said standard and engaging the threads thereof, a hollow lifting element mounted for axial movement in said standard and having an internally threaded portion, a screw rigidly secured to said nut and engaging the threaded portion of said lifting element, and means for rotating said nut and said screw.

9. In a lifting jack, a hollow standard having internal screw threads, a nut rotatably mounted in said standard and engaging the threads thereof, a hollow lifting element mounted for axial movement in said standard and having an internally threaded portion, a screw rigidly secured to said nut and engaging the threaded portion of said lifting element, an actuating bar having slidable but non-rotatable connection with said nut and said screw, and means for rotating said bar.

10. In a lifting jack, a hollow standard having internal screw threads, a nut rotatably mounted in said standard and engaging the threads thereof, a hollow lifting element mounted for axial movement in said standard and having an internally threaded portion, a screw rigidly secured to said nut and engaging the threaded portion of said lifting element, an actuating bar having slidable but non-rotatable connection with said nut and said screw, a sleeve supported by and held against rotation with said nut, extending about said lifting element and having means for holding said lifting element against rotation, and means for rotating said bar.

11. In a lifting jack, a hollow standard having internal screw threads, a nut rotatably mounted in said standard and engaging the threads thereof, a hollow lifting element mounted for axial movement in said standard and having an internally threaded portion, a hollow screw engaging the threaded portion of said lifting element and having a portion extending through and rigidly secured to said nut, an actuating bar extending into said screw and held against rotation with relation thereto, and means for rotating said bar.

12. In a lifting jack, a hollow standard having internal screw threads and having an enlarged lower portion forming a base, a nut mounted in the threaded portion of said standard, a hollow lifting element mounted for axial movement in said standard and having an internally threaded portion, a screw rigidly secured to said nut and engaging the threaded portion of said lifting element, an actuating bar rotatably mounted in said base and having slidable but non-rotatable connection with said screw, a gear rigidly secured to said bar, and means for actuating said gear.

13. In a lifting jack, the combination of an internally threaded standard, a vertically

disposed driving spindle rotatably mounted in said standard and provided with a beveled gear at its lower end, a driving gear mounted on said standard to coact with said gear on said spindle, an actuating screw having 76 splined driving engagement with said spindle and provided with a threaded lower portion coacting with the threads of said standard and with an oppositely threaded upper portion, a hollow lifting member telescopingly associated with the upper portion of said actuating screw and having threaded engagement therewith, a housing sleeve embracing said upper portion of said screw and telescopingly associated therewith and with said standard, and means for preventing rotation of said lifting member.

14. In a lifting jack, the combination of an internally threaded standard, a vertically disposed driving spindle rotatably mounted in 85 said standard, an actuating screw having splined driving engagement with said spindle and provided with a threaded lower portion coacting with the threads of said standard and with an oppositely threaded upper portion, a hollow lifting member telescopingly associated with the upper portion of said actuating screw having threaded engagement therewith, and a housing sleeve embracing said upper portion of said screw and telescopingly associated therewith and with said standard, and means for preventing rotation of said lifting member.

15. In a lifting jack, the combination of an internally threaded standard, a vertically disposed driving spindle, an actuating screw having splined driving engagement with said spindle and provided with a threaded lower portion coacting with the threads of the standard and with an oppositely threaded upper portion, a lifting member having threaded engagement with the upper portion of the screw, a housing member telescopingly associated with said standard and lifting member, and means for preventing rotation of the 110 lifting member.

16. In a lifting jack, the combination of a standard having internal screw threads, a vertically disposed driving spindle, an actuating screw having splined driving engagement with said spindle and provided with a threaded lower portion coacting with the threads of the standard and with an externally and oppositely threaded upper portion, a lifting member having threaded engagement 115 with the upper portion of the screw and means for preventing rotation of said lifting member.

17. In a lifting jack, the combination of a standard having internal screw threads, a vertically disposed driving spindle, an actuating screw having splined driving engagement with said spindle and provided with a threaded lower portion coacting with the threads of the standard and with an external- 125

ly and oppositely threaded upper portion, a lifting member having threaded engagement with the upper portion of the screw, and means collapsible within said standard for preventing the rotation of said lifting member.

18. In a lifting jack, the combination of a standard having internal screw threads, a vertically disposed driving spindle, an actuating screw having splined driving engagement with said spindle and provided with a threaded lower portion coaxing with the threads of the standard and with an externally and oppositely threaded upper portion, a lifting member having threaded engagement with the upper portion of the screw, and a member telescopingly and non-rotatably associated with said standard and lifting member.

19. In testimony whereof, I affix my signature hereto.

ION VON KERT HOTT.
